UNITED STATES PATENT OFFICE

122,581

DESIGN FOR A HANGING LIGHTING FIXTURE

Charles Boghos Arakelian, Watertown, Mass.

Application May 16, 1940, Serial No. 92,416

Term of patent 7 years

To all whom it may concern:

Be it known that I, Charles Boghos Arakelian, a citizen of the United States, residing at Watertown, in the county of Middlesex and State of Massachusetts, have invented a new, original, and ornamental Design for a Hanging Lighting Fixture, of which the following is a specification, reference being had to the accompanying drawing, forming part thereof.

I claim:

The ornamental design for a hanging lighting fixture, as shown.

CHARLES BOGHOS ARAKELIAN.
